UNITED STATES PATENT OFFICE.

WILLIAM R. CHAMBERLAIN, OF MOUNT VERNON, NEW YORK.

DESIGN FOR A LAMP FIXTURE.

Application filed December 21, 1928. Serial No. 29,357. Term of patent 14 years.

To all whom it may concern:

Be it known that I, WILLIAM R. CHAMBERLAIN, a citizen of the United States, residing at Mount Vernon, county of Westchester, and State of New York, have invented a new, original, and ornamental Design for Lamp Fixtures, of which the following description in connection with the accompanying drawing is a specification.

Fig. 1 is a front elevation, and
Fig. 2 is a side elevation of a lamp fixture, showing my new design.

I claim as my invention:
The ornamental design for a lamp fixture,
substantially as shown.

WILLIAM R. CHAMBERLAIN.
